United States Patent Office.

THOMAS S. BLAIR, OF PITTSBURG, PENNSYLVANIA.

Letters Patent No. 91,901, dated June 29, 1869.

IMPROVED APPARATUS FOR THE MANUFACTURE OF PIG-BLOOMS.

The Schedule referred to in these Letters Patent and making part of the same.

To all whom it may concern:

Be it known that I, THOMAS S. BLAIR, of the city of Pittsburgh, in the county of Allegheny, and State of Pennsylvania, have invented a new and useful improved Apparatus for the Manufacture of Pig-Blooms; and I do hereby declare the following to be a full, clear, and exact description thereof.

My invention consists in improved apparatus for mixing molten iron and pulverized ore, oxides, or other ingredients, which are mixed with the molten metal, to form the conglomerate known as "pig-bloom" or "pig-scrap," in the process of making malleable iron from crude metal, known as the "Ellershausen process," described in Letters Patent of the United States, dated November 17, 1868, granted to Francis Ellershausen, Augustus E. Stayner, and Adolph Guzman.

In mixing the molten cast-iron with the pulverized iron ore, or other material used for making the conglomerate, as described in the patent referred to, it is very important that the pulverized iron ore and melted cast-iron should be mixed by pouring them simultaneously in separate streams, which unite so as to form the conglomerate, whether in a mould or on any suitable receiving-surface.

The method particularly described is the use of an ingot-mould, into which the streams of molten iron and pulverized ore are poured simultaneously and stirred, their union immediately chilling the iron, and forming the solid substance called conglomerate.

For this reason it is practically impossible to produce any good result by trying to mix the oxide by pouring and stirring it into a receptacle previously filled with molten iron, because the contact of the iron ore or oxide immediately congeals and stiffens the iron, preventing the stirring, and resulting in a union of only a slight amount of the molten iron on the surface with the oxide.

The mode of pouring together the molten iron and oxides in simultaneous streams, as described in the Ellershausen patent referred to, effectually accomplishes the desired result, but requires too much manual labor, and cannot be so conveniently operated, on a large scale, as the apparatus I have invented for the purpose, and which I will proceed to describe, reference being had to the accompanying drawings, forming part of this specification, in which—

Figure 1 is a perspective representation of my apparatus.

Figure 2 is a vertical section through the revolving table shown in fig. 3.

Figure 3 is a perspective representation, showing the apparatus in operation, and dispensing with the use of a receiver intermediate between regulators and the blast-furnace.

In the several figures, like letters denote the same parts.

The apparatus consists of three principal parts:

First, a revolving-table, with or without partitions, on which the molten iron and pulverized ore are mixed to form the "pig-bloom" or "pig-scrap."

Second, a spout for delivering the powdered ore or oxide in a steady, thin stream on the revolving-table.

Third, a regulator for pouring a steady stream of molten iron on the revolving-table simultaneously with the ore or oxide.

The revolving-table consists of an annular horizontal plate, *a*, which is made of iron, and may be of any convenient size, (say fourteen feet diameter, more or less,) made, if need be, in pieces bolted together.

This plate is supported on friction-rollers *b*, (see fig. 2,) set in blocks *f*, in a circle under the horizontal plate, the rollers working in a groove in the under side of the plate *a*.

To the outer edge of the plate *a* are attached segmental pieces *h*, having cog-teeth, forming a continuous circular toothed rack, around the under side of the plate *a*. Into this gears a cog-wheel or pinion, *c*, fig. 2, by which the annular table is caused to revolve on the friction-rollers, motion being communicated to the cog-wheel from the steam-engine, or other prime motor, and so arranged that it can be stopped and started at pleasure.

The annular table is formed into a trough by means of inner side-pieces *d*, on the inner side, which are bolted to each other, and to the bottom plate *a*, and outer side-pieces *e*, which are not bolted to the table, but set in a groove near the edge of the annular table *a*, and united together at top by means of lugs *i*, projecting from the side-pieces and keys *k*, placed in the lugs, so that, when it is desired to remove the conglomerate from the trough or mould formed by the annular table, the keys are struck out from the lugs, when the outer side-pieces *e* are easily removed.

Loose partitions *l*, being rectangular plates of iron, are set radially on the annular table, between the inner and outer side-pieces *d* and *e*, at regular intervals, thus dividing the trough of the table into a number of cavities of uniform shape, in which the "pig-bloom" may be formed.

A block, or pillar, *m*, is placed within the annular table, near to the annular trough. This block *m* supports a spider, *n*, consisting of three branches, to any one or more of which is attached a regulator, consisting of an iron box, *p*, with a spout, *q*, the width of the spout being about equal to the width of the trough in the annular table, and of the required width of the stream of melted metal.

The block *m* and spider *n* are so arranged, relatively to the trough, as that any one of the three regulators may be turned, so that its spout *q* shall deliver the stream of melted metal into the trough of the annular table as it revolves.

In order to regulate with accuracy the flow of metal

I propose to use also a reservoir, *r*, (see fig. 1,) into which the molten metal is first poured from the blast-furnace or cupola, and then, by raising the bearings *s* of the reservoir, by means of hydraulic pressure or otherwise, and tilting it, the metal is run out into the regulator *p*, thence, through its spout *q*, into the trough of the annular table.

If preferred, the use of the reservoir may be dispensed with, and the melted metal run immediately from the furnace *t* into the regulator *p*, as shown in fig. 3.

At any convenient point near to the revolving-table is placed a box, *u*, for pulverized ore, which may be kept filled, as required, by means of an elevator, *v*, of any convenient construction, or otherwise.

A spout, *w*, conducts the pulverized ore into the trough of the annular table from the ore-box *u*, whenever the gate *x* is raised by the workman, the amount of ore delivered being regulated by a workman, by raising the gate *x* more or less.

The mouth of the ore-spout *w* is placed over the trough of the revolving-table, near to the mouth of the metal spout *q*, but not touching, so that the streams of ore and metal, simultaneously pouring into the trough, may be intimately commingled, or placed a little further apart, so that one may immediately overlie the other.

The apparatus being thus constructed, its operation is very simple. The inner sides of the trough, formed by the bottom and side-plates of the table, and the partition-plates, are all "daubed" in the usual manner. As the metal is poured, in a thin, broad stream, into the annular trough, it is immediately covered by a thin, broad stream of ore, and so on continuously. As the table revolves, the ore is sandwiched between layers of melted metal; and this process is continued until the trough is full.

As the metal congeals immediately on contact with the ore, a solid mass of conglomerate is formed, and almost immediately after the trough is full the outer-side-pieces *e* are removed by striking away the keys *k* from the lugs *i*, and, the partitions *l* being then loose, the masses of pig-bloom may be immediately removed,

and the trough of the revolving-table emptied for a repetition of the process.

If it is desired to form "pig-scrap" instead of "pig-bloom," a revolving table may be used, without partitions or sides, and the melted iron be poured on the ore deposited upon the table. My apparatus is, however, especially adapted to the manufacture of pig-bloom.

I do not desire to confine myself to a revolving or circular-table, as an oscillating motion might be given to a straight table and the same result be produced.

I do not desire to claim the process of making malleable iron by the mixture of molten metal and pulverized ore, so as to form pig-bloom or pig-scrap in the manner known as the Ellershausen process; but

What I do claim as my invention, and desire to secure by Letters Patent, is—

1. The moving-table, with or without partitions and side-pieces, in combination with a spout for delivering the molten metal, and a spout for delivering the pulverized oxide or oxides simultaneously upon the surface, or into the trough of the moving table, for the manufacture of pig-bloom or pig-scrap, substantially as described.

2. A circular table, having removable outer pieces or curb, and partitions, constructed substantially as described, for the purpose set forth.

3. The combination of the moving table with one or more regulators *p*, for receiving and delivering the molten iron on the moving table, in a regular and uniform stream, substantially as and for the purpose hereinbefore described.

4. In combination with the moving table and regulator or regulators, the reservoir *r*, for receiving the molten metal from the blast-furnace or cupola, and pouring it into the regulator, so as more easily to control its flow upon the moving table, substantially as hereinbefore described.

In testimony whereof, I, the said Thomas S. Blair, have hereunto set my hand.
